UNITED STATES PATENT OFFICE

101,909

DESIGN FOR A MASHING APPARATUS OR SIMILAR ARTICLE

Harold K. White, George A. Stephen, and Louis Ehrenfeld, Chicago, Ill., assignors to Weber Bros. Metal Works, Chicago, Ill., a corporation of Illinois

Application August 24, 1936, Serial No. 64,538

Term of patent 7 years

To all whom it may concern:

Be it known that we, Harold K. White, George A. Stephen, and Louis Ehrenfeld, all citizens of the United States and residents of the city of Chicago, in the county of Cook and State of Illinois, have invented a new, original, and ornamental Design for a Mashing Apparatus or Similar Article, of which the following is a specification, reference being had to the accompanying drawing forming a part thereof.

On the drawing:

The figure is an isometric view of the mashing apparatus, showing our new design.

The reverse side of the apparatus is a continuation of the general features shown, and the apparatus as shown is in an operating position.

We claim:

The ornamental design for a mashing apparatus or a similar article, as shown and described.

HAROLD K. WHITE.
GEORGE A. STEPHEN.
LOUIS EHRENFELD.
